UNITED STATES PATENT OFFICE

144,947

DESIGN FOR A CABINET FOR A DISK DICTATING MACHINE

Robert L. Stone, Guilford, Conn., assignor to The
Soundscriber Corporation, New Haven, Conn.,
a corporation of Connecticut

Application October 22, 1945, Serial No. 123,097

Term of patent 14 years

(Cl. D56—4)

To all whom it may concern:

Be it known that I, Robert L. Stone, a citizen
of the United States, residing in the town of
Guilford, county of New Haven, and State of
Connecticut, have invented a new, original, and
ornamental Design for a Cabinet for Disk Dic-
tating Machine, of which the following is a spec-
ification, reference being had to the accompany-
ing drawings, forming a part thereof.

Fig. 1 is a side elevational view of a cabinet
for disk dictating machine, showing my new de-
sign.

Fig. 2 is a top plan view of the same.

Fig. 3 is a front elevational view of the same.

Fig. 4 is a rear elevational view of the same.

Fig. 5 is a bottom plan view of the same.

The characteristic features of my design re-
side in the portions shown by means of full lines
in the drawings.

I claim:

The ornamental design for a cabinet for a disk
dictating machine, as shown and described.

ROBERT L. STONE.
